UNITED STATES PATENT OFFICE.

ALBERT H. KOLKER, OF CHICAGO, ILLINOIS.

DESIGN FOR A NUT-BOWL.

51,071.

Specification for Design.

Patented July 24, 1917.

Application filed May 7, 1917. Serial No. 167,139. Term of patent 3½ years.

To all whom it may concern:

Be it known that I, ALBERT H. KOLKER, a citizen of the United States, residing at Chicago, in the county of Cook and State of Illinois, have invented a new, original, and ornamental Design for Nut-Bowls, of which the following is a specification, reference being had to the accompanying drawing, forming part thereof.

The figure is a perspective view of a nut bowl, showing my new design.

I claim:

The ornamental design for a nut bowl, as shown.

ALBERT H. KOLKER.
